UNITED STATES PATENT OFFICE.

WALTER LENCHARD, OF MCKEESPORT, PENNSYLVANIA.

TOY DOLL.

1,350,660.

Specification of Letters Patent. Patented Aug. 24, 1920.

Application filed November 1, 1919. Serial No. 334,999.

To all whom it may concern:

Be it known that I, WALTER LENCHARD, a citizen of the United States, residing at McKeesport, in the county of Allegheny and 5 State of Pennsylvania, have invented new and useful Improvements in Toy Dolls, of which the following is a specification.

This invention relates to a toy doll, and more particularly to a doll or figure of that 10 type which is normally held in an upright position through the medium of a weight member.

One of the main objects of the invention is to provide a doll or figure employing a 15 weight member which may be adjusted within the body of the figure so as to vary the height of its point of gravity thus causing the body to either stand up or lie down as desired. A further object is to provide a 20 doll or figure having means associated with the weight adjusting means for causing movement of the arms of the figure giving it the semblance of raising itself when held at an inclination to permit lowering of the 25 weight. Another object is to provide a figure of suitable construction which may be readily produced and sold at small cost. Further objects will appear from the detailed description.

30 In the drawings:

Figure 1 is a front view, partly broken away, of a toy doll constructed in accordance with my invention.

Fig. 2 is a fragmentary sectional view 25 through a modified form.

Fig. 3 is a central sectional view through another modified form.

Fig. 4 is a side view, partly broken away, of still another modified form.

40 Referring more particularly to Fig. 1, the body 1 of the figure, which may be of any preferred size and shape, is preferably provided with a rounded base 2 and has a central cylindrical bore 3 within which is slid- 45 ably mounted a weight 4, the lower end of this bore being closed by a plug 5. Weight 4 is connected by a cord 6 to a rotatably mounted shaft 7 passing through what might be considered the shoulder portion 1^a 50 of the body, arms 8 being secured upon this shaft adjacent each end thereof. When the weight 4 is in lowered position, as illustrated, the center of gravity of the figure as a whole is positioned below the vertical 55 center thereof so that the figure is caused

to stand in an upright position. By rotating shaft 7, by means of arms 8, cord 6 may be readily wound onto the shaft thus raising the weight causing the body 1 to tilt over and lie down. If the head 9 of the 60 body be raised so as to support the body at an inclination, weight 4 will travel downwardly in bore 3 thus unwinding cord 6 from shaft 7 and causing rotation of the arms 8 imparting to the figure the appearance of attempting to raise itself into upright position.

In Fig. 2 I have provided a resilient catch 10 which extends slightly into bore 3. The object of this catch is to releasably hold 70 weight 4 in its lowermost position so as to prevent accidental sliding of this weight toward head 9 in the event that the base portion of the figure is elevated, the object being to insure that when the weight is raised the 75 cord will be wound upon the shaft so as to rotate this shaft and the arms in the manner previously described.

In the form illustrated in Fig. 3, a cord 6^a has its intermediate portion wrapped 80 about shaft 7 in opposite directions, one end of this cord being secured to the upper end of weight 4, and the other run 6^b of the cord being passed downwardly through an eye 11 projecting into bore 3, this eye being horizontally disposed, and then through a vertically disposed eye 12 secured centrally of the upper face of plug 5, the cord being then secured to an eye 13 positioned centrally of the lower end of the weight. By this construction I prevent free sliding movement 90 of weight 4 within bore 3 and also insure that the arms 8 of the figure will be rotated when the weight is moved in either direction.

95 In the form illustrated in Fig. 4, figure 1^b is provided with a central bore 3^a the lower end of which is closed by a plug 5^a. A spherical weight member 4^a is positioned within the bore and is held in vertical adjustment therein by means of a pin 14 extending through the front portion of the body, this pin being provided on its outer end with a button head 15 which resembles in appearance button members 16 secured to 100 the front of the body. By withdrawing the pin 14 the weight 4^a may be caused to move into the upper portion of bore 3^a and, by again inserting the pin, may be held in this 105 position thus raising the center of gravity 110

of the device as a whole so that the body may be readily caused to lie down, or stand up, as desired.

As suggested, there might be slight variations made in the details of construction and arrangement of my invention without departing from the field and scope of the same, and I intend to include all such variations, as fall within the scope of the appended claims, in this application in which the preferred forms only of my invention are disclosed.

What I claim is:

1. In a device of the character described, a body provided with a central vertical bore, a weight member slidable in said bore, and means for adjusting said weight member vertically for varying the position of the center of gravity of the device.
2. In a device of the character described, a body provided with a central bore, a weight member slidable within said bore, a shaft rotatably mounted through the body and extending across the bore remote from the lower end thereof, and connections between said shaft and the weight member for rotating said shaft in accordance with raising or lowering of the weight member.
3. In a device of the character described, a body provided with a central vertical bore, a shaft rotatably mounted through the body

and extending across said bore adjacent the upper end thereof, a weight member slidable in the bore of the body, and a cord connecting said weight member to the shaft so as to cause rotation thereof in accordance with movement of the weight member.

4. In a device of the character described, a body having a central vertical bore, a weight member slidable in said bore, a shaft rotatably mounted through the body and extending across the bore adjacent the upper end thereof, arms attached to said shaft for rotation therewith, and a flexible member connecting the weight member to the shaft for causing rotation thereof in accordance with movement of said weight member.

5. In a device of the character described, a body having a central vertical bore, a weight member slidable in said bore, a shaft rotatably mounted through the body and extending across the bore adjacent the upper end thereof, arms attached to said shaft for rotation therewith, and a flexible member connecting the weight member to the shaft for causing rotation thereof in accordance with movement of said weight member, and means for releasably holding the weight member in lowered position.

In testimony whereof I affix my signature.

WALTER LENCHARD.
